UNITED STATES PATENT OFFICE.

CHARLES DOUGLAS WINFIELD, OF BROOKLYN, NEW YORK.

DESIGN FOR A CANDLE-HOLDER AND PENDANT.

SPECIFICATION forming part of Design No. 24,548, dated August 13, 1895.

Application filed June 22, 1895. Serial No. 553,717. Term of patent 7 years.

To all whom it may concern:

Be it known that I, CHARLES DOUGLAS WINFIELD, a citizen of the United States, residing in Brooklyn, in the county of Kings and State of New York, have invented or produced a new and original Design for Candle-Holders, of which the following is a specification.

This design relates particularly to candle-holders of the class having a holder at top, a hooked stem, and a counterbalancing-weight, such holders being hung upon a support and maintained in the upright position by the weight.

The new design is illustrated in the accompanying drawing, which is a perspective view of a candle-holder having the new design.

Referring to the drawing, the holder has a top member A, a part B extending therefrom downwardly, and a pendant or body C at the lower end of the part B. The top member A has a plurality of flat upright separated projections *a* and a plurality of concave or corrugated outwardly and upwardly extending wings *b* opposite the spaces between the projections *a*, a flat or concave bottom *c* within the wings and projections, substantially parallel spaces *d* between the wings, and upright spaces *e* between the projections. It has the appearance of a circular irregular star-shaped figure.

The part B is an elongated member of cylindrical cross-section having a curved part *f* extending in substantially a half-circle beneath the part A, a straight downwardly-extending part *g* of considerable length extend-

ing from this curve to the part C, a straight downwardly and laterally inclined part *h* extending from the other side of the curve downwardly a short distance, a small reverse curve at the lower end of this part, and a straight 40 upwardly-extending part *j* parallel with the part *g* extending from the curve *i* upwardly under one of the wings *b* and through and above this wing.

The part C at the lower end of the part B 45 has an elongated bulbous shape, with a relatively smooth upper end *k* approximating in its general contour a hemisphere, and a tapering and contracting lower end *l*, approaching substantially to a point at bottom. On the 50 end *k* are small roughenings *m*, gradually increasing in size and leading into large roughenings *n* extending down the body with increasing projection to the point *l*.

The holder and pendant embodying the new 55 design have a pleasing appearance to the eye, the part A presenting the appearance of a light fragile upper member, the part C a graceful tapering pendant, and the part B a slender intermediate strand. 60

What I claim is—

The design for a candle holder and pendant substantially as shown and described.

In witness whereof I have hereunto signed my name in the presence of two subscribing 65 witnesses.

CHARLES DOUGLAS WINFIELD.
